UNITED STATES PATENT OFFICE.

FREDERICK AUGUSTUS ROWE, OF NORTH VANCOUVER, BRITISH COLUMBIA, CANADA,
ASSIGNOR OF ONE-HALF TO EDWARD WINTHROP PELTON, OF VANCOUVER,
CANADA.

HOSE-SUPPORTER.

1,102,804.

Specification of Letters Patent.

Patented July 7, 1914.

Application filed June 20, 1913. Serial No. 774,848.

To all whom it may concern:

Be it known that I, FREDERICK AUGUSTUS ROWE, a citizen of the United States, and residing at the city of North Vancouver, in the Province of British Columbia, Canada, have invented certain new and useful Improvements in Hose-Supporters, of which the following is a specification.

My invention relates to improvements in hose supporters, and the object of my invention is to devise a simple and inexpensive hose supporter which can be readily attached to the lower extremities of the elastic supports provided on corsets or like garments for this purpose, and which, by supporting the hose by its folded over edge or top portion and by spreading the supporting strain on the threads of the hose over a wider area than is obtained in the present forms of hose supporters, will prevent the tearing of the hose caused at the present time by inefficient forms of supporters in which the strain is concentrated at one point.

A further object is to devise a hose supporter which will support the hose without tearing it which will do away with the use of garters, bands or the like, and provide a quick, easy, and efficient means of fastening.

I attain these objects by the means illustrated in the accompanying drawings in which—

Figure 1 is a view illustrating my invention supporting a stocking. Fig. 2 is an elevation of the clasp of my supporter. Fig. 3 is a side elevation of the clasp. Fig. 4 is a plan view of the stamping before being formed into the finished button plate. Fig. 5 is a front elevation of the button plate. Fig. 6 is a side elevation of the complete button plate. Fig. 7 is a side elevation of my complete hose supporter, open. Fig. 8 is a side elevation of my complete supporter closed. Fig. 9 is an elevation of Fig. 8.

Similar letters refer to similar parts throughout the several views.

A is the slotted clasp of my supporter, preferably formed substantially J-shaped as shown in Fig. 2, adapted to be fastened by its top end to corsets or other like garments by elastic supports as shown at A¹ in Fig. 1, and to engage at its lower end into a button plate by its upwardly turned ends A² and to be held therein by the spring action of these ends and the points A³.

B is the button plate of my supporter, 55 and is formed by stamping a piece of any suitable material to a shape preferably similar to that shown in Fig. 4, in which B¹ represents the stamping, B² is a raised portion to form the stem of the button having a bore 60 therein through which the rivet passes, and B³ is the slot which provides the opening in the finished button plate for the points A A³ to pass through and engage the button plate B. 65

B⁴ is a countersunk hole into which the end of the rivet is beaded over to hold same securely to the plate.

After the material has been stamped out, as shown in Fig. 4, it is bent double as shown 70 in Figs. 5 and 6, so that the hole in B² will be directly opposite the hole B⁴. A piece of felt B⁵, or other similar material, is placed between the faces to project beyond the edges and held therebetween by the sides of the 75 plate being pressed tightly against it, and by the rivet. This felt, B⁵, is cut as shown by the dotted line, B⁶ in Fig. 5, to allow the rivet to pass through from one side of the plate to the other, and also to allow of the 80 points A³ passing up into the button plate, from which it will be seen that there is a space left inside the finished button plate enclosed by the dotted line B⁶ and equal in width to the thickness of the felt B⁵. 85

B⁷ is a rivet which passes through the hole in the raised portion B² and the hole B⁴, its end being riveted over into the countersink of the hole B⁴.

B⁸ is a piece of felt or other similar material placed on the end of the raised portion B² and through which the rivet B⁷ passes. When the rivet has been firmly riveted to the plate, the felt B⁸ is tightly secured between the head of the rivet and the end of 95 the raised portion B² and in combination with the rivet head forms the head of the button, the felt being for the purpose of locking the button plate to the clasp when closed and also to prevent damage to the 100 hose at this point.

The manner in which my supporter is assembled is shown in Fig. 7, that is, the upwardly turned ends A² of the clasp A are pressed inward until the points A³ are enabled to pass through the slot B³, after which the pressure on the ends A² is released, when they immediately spread out 105

wardly to fill the length of the slot and hook the points A³ inside the button plate B, which is thus securely held to the clasp, at the same time being free to swivel or move upwardly or downwardly thereon.

The manner in which my supporter is used is shown in Fig. 1, Fig. 7 and Fig. 8, and is as follows:—The supporter is held in the open position, as shown in Fig. 7, 10 with the button plate pressed against the outside of the stocking, far enough down from the top edge to allow of the edge or top portion of the stocking being folded over the button plate and down into the 15 clasp, all as shown in Fig. 7, the edge of the stocking being indicated by the dotted line C. The button plate B is then swung upward into a vertical position, as shown in Fig. 8, thus inclosing the folded over edge 20 of the stocking between the button plate and the clasp and engaging over the head of the button, which projects through the wide part of the clasp to the far side, all as shown in Fig. 8, the stocking being indicated by 25 the dotted line C. If now the button plate be pressed downward as far as it will go, the head of the button will be engaged by the clasp, as shown in Figs. 8 and 9, to prevent the supporter from coming open until 30 the button plate has been moved up again, and thus the stocking will be securely fastened by its edge or top portion folded over the edge of the button plate, and the edge of the plate and the head of the button being of felt, there will be no danger of 35 damage to the stocking at this point, from which it will be seen that the strain on the threads of the stocking will be distributed over the edge of the button plate, and this, 40 in combination with the folded over edge or top portion, effectually prevents the tearing or "holing" of the hose which is so common at the present time with the present forms of hose supporters.

45 It will be seen, therefore, that I have devised a simple and inexpensive hose supporter which can be readily attached to corsets or like garments, and which, by supporting the hose by a fold therein and by 50 spreading the supporting strain over a much wider area than is obtained in the present forms of hose supporters, will prevent the tearing of the hose caused at the present time by the strain being concentrated at one 55 point. It will be seen further that I have devised a hose supporter which will support hose without tearing same and without the use of garters, bands, or the like, and which will provide a quick, easy, and efficient means of fastening.

60 What I claim as my invention is.

1. In a garment supporter, a depending member, and a co-acting supporting plate having means for retaining the fabric at one 65 side in such a position that it passes over

the upper edge in a fold and hangs unobstructed downwardly upon the opposite side.

2. A hose supporter comprising a depending member and a relatively movable co-acting plate normally held under strain parallel to the member and means for normally holding the fabric between it and the member and yet allow of such fabric passing upwardly between the plate and member and 70 folding over the top edge of the plate and hanging directly therefrom, so that the strain on the fabric is equally divided on both sides of the upper edge of the plate and the tearing of the fabric is prevented as 75 specified.

3. A hose supporter comprising a vertically slotted member and a co-acting plate normally held under strain and means co-operating with the slotted member for holding the fabric between it and the slotted member and yet allowing of such fabric passing upwardly between the plate and the slotted member and folding over the top 85 edge of the plate and hanging freely behind 90 the plate from such edge as specified.

4. A hose supporter comprising a depending member and a co-acting plate normally held under strain parallel to the member and means for adjustably connecting it to the member, whereby its relative position to the member may be primarily changed, so as to receive the fabric and means for normally holding the fabric between it and the member, and yet allow of such fabric passing upwardly between the plate and the member and folding over the top edge of the plate and hanging directly therefrom, so that the strain on the fabric is equally divided on both sides of the upper edge of the plate 100 and the tearing of the fabric is prevented 105 as specified.

5. A hose supporter comprising a depending member and a co-acting member provided with a yielding upper edge secured 110 adjacent to the depending member, and means for gripping the fabric between the two members, so that the fabric passes from the gripping point upwardly and folds over and passes downwardly from the top and 115 on the opposite side of the coacting member as specified.

6. A hose supporter comprising a depending member and a co-acting member provided with a yielding upper edge adjustably secured adjacent to the depending member, and means for gripping the fabric between the two members, so that the fabric passes from the gripping point upwardly and folds over and passes downwardly from the top of the co-acting member as specified.

7. In a hose supporter, the combination with the hose supporter band, of a J-shaped member secured to the supporter band and having a vertically slotted portion and a 130

portion having a broad arc-shape upper edge slidably carried by the upwardly extending portion or short arm of the J-shaped member, and slidable engaging means between the portion having the arc-shape edge and that portion of the vertical slot extending through the body of the J-shaped slotted member, as and for the purpose specified.

8. In a hose supporter, the combination with the supporter band, of a J-shaped member secured to the supporter band, a member having a broad arc-shaped upper edge slidably carried when in a vertical position by the short arm of the J-shape member, and connecting means between the arc-shaped member and the upper end of the short arm of the J-shape member adapted to allow of an outward swinging movement from the slotted member of the member having the arc-shape edge, and engaging means on the outer face of the member having the arc-shape edge and the J-shape member, as and for the purpose specified.

9. In a hose supporter, the combination with the hose supporter band, of a slotted J-shape member connected to the supporter band and having the slot enlarged in proximity to the band, of a button plate having a broad arc-shape upper edge, and a pivotal connection between its lower edge and the upper end of the short arm of the J-shape member, and capable of slidable vertical movement on the short arm of the J-shape member, and a button head extending from the outer face of the plate and designed to extend through the slotted enlargement when the button plate is thrown upwardly against the body of the J-shape member and designated to engage with the lower portion of the slot beneath such enlargement when the button plate is slid vertically downwardly, as and for the purpose specified.

10. In a hose supporter, the combination with the hose supporter band, of a J-shaped slotted member connected to the band and having the slot enlarged in proximity to the band and having a pivot portion extending laterally from the short arm thereof, of a hollow button plate having a broad arc-shape upper edge, and an opening in its lower edge into which the short arm of the J-member slidably extends whereby a swingable connection is formed between the upper end of the short arm of the J and the button plate when the button plate is in its upper position, and a button head extending from the outer face of the button plate designed

to extend through the slot enlargement and to pass downwardly into the slot when the button plate is slid vertically downwardly 60 on the short arm of the J-member, as and for the purpose specified.

11. A hose supporter comprising a depending member and a co-acting member adjustably swung on the lower end of the 65 depending member, and means on its face for gripping the fabric between the two members, so that such fabric passes upwardly between the two members when in the closed position and folds over the top 70 edge of the co-acting member, and hangs directly down from the opposite side as specified.

12. A hose supporter comprising a depending member having a vertical slot provided with an enlargement intermediate of its length, and a co-acting member adjustably swung on the lower end of the depending member, and a button on its face on which the fabric is placed and designed to 80 be passed through the enlargement in the depending member when it is being swung into position and to slide down to grip the fabric between the narrow portions of the slot, so that the fabric is held thereby and 85 will pass upwardly over the top edge of the co-acting member and hang down from the opposite side thereof as specified.

13. A hose supporter comprising a depending member formed in two legs having 90 turned up lower ends with laterally extending projections, and a co-acting member slidably held on the turned up ends and designed to pivot on the lateral extensions to swing, and means for gripping the fabric 95 between the co-acting member and the depending member, whereby the fabric passes upwardly at one side over the upper edge of the co-acting member and downwardly on its opposite side when the co-acting plate 100 is in the closed position as and for the purpose specified.

14. In a device of the class described, a button plate adapted to be held on a depending member and formed up in a fold 105 out of one piece, and a piece of yielding material held between the parts and projecting beyond the edge of the plate as specified.

Dated at Vancouver, B. C. this 2nd day of June, 1913.
